MATERIAL HANDLING APPARATUS

William Ruddock, South Pasadena, Calif., assignor of one-half to Marion P. McCaffrey, Los Angeles, Calif.

Application January 20, 1943, Serial No. 472,978

10 Claims. (Cl. 214—140)

This invention relates to material handling apparatus. More particularly it relates to shock absorbing means for use in connection with the movable bucket or material engaging element commonly used on such apparatus. This application relates to an improvement of apparatus such as disclosed in an application entitled "Material handling apparatus," filed November 10, 1941, in the name of William Ruddock, and bearing Serial No. 418,557, now Patent No. 2,362,406, granted November 7, 1944.

Such apparatus includes a bucket or the like attached to an arm which is adapted to be raised, lowered or otherwise moved so as to load or unload the bucket, or to transport the loaded bucket.

The capacity of machines of this nature is to some extent restricted by the width of the bucket. Thus, to provide suitable capacity as well as to provide machines for special purposes, for example wherein the bucket acts as a scraper, it is common to utilize a relatively wide bucket or material engaging element. This necessitates the provision of means which will apply the lifting force to the bucket at two points which are widely spaced transversely of the bucket.

A cable or cables are commonly used to transmit force to such buckets from a drum mechanism operated by a source of power on the apparatus, although chains might be used, or an element composed partly of rods and cables or chains.

When a pair of such cable elements are used, as for lifting a wide bucket, it is preferable to provide equalizing means which will insure equal stresses in the cable elements. This not only avoids the difficulty of initially adjusting the parts to obtain equal tension in the cables, but also compensates for variations due to operating conditions, such as unequal spooling of the cables on the winding drum, unequal distribution of load in the bucket, etc.

Further, in such apparatus, whether using a pair of cable elements or not, the cable element as well as the entire machine is subject to severe shock and stress due to sudden stoppage of the loaded bucket as by application of the brakes which control the drum mechanism. Severe shocks to the machine may also result from the bucket encountering hard or fixed objects in the material being handled, or in loading mixtures of materials of different characteristics of weight, hardness, or the like.

It is an object of the present invention to provide improved means for absorbing such shocks.

It is another object of this invention to provide means providing resilience in the connection between the cable element and the material engaging element.

5 It is another object of this invention to provide a novel form of shock absorber for material handling equipment.

It is still another object of this invention to provide improved means for equalizing the forces in the cable elements of such apparatus.

It is still a further object of this invention to provide shock absorbing means and equalizing means which cooperate and form a simple, compact arrangement.

This invention possesses many other advantages, and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, 20 since the scope of the invention is best defined by the appended claims.

Referring to the drawing:

Figure 1 is a side elevation of one type of material handling apparatus with which the present invention may be employed;

30 Figure 2 is a detail plan of the bucket and outer end of the hoisting arm;

Figure 3 is a longitudinal section of the shock absorbing mechanism, on an enlarged scale;

35 Figure 4 is a view looking upward from the bottom of Figure 3; and,

Figure 5 is a fragmentary elevation of a modified form of the invention.

Referring to the drawing, there is shown in 40 Figure 1, a tractor shovel, which may be of that type disclosed in my Patent No. 2,260,539, issued October 28, 1941, and entitled "Tractor shovel."

This machine comprises a frame 10, arranged for movement over the ground, as by being mounted 45 on Caterpillar tracks 11. A hoisting arm or boom 12 is pivotally supported on the frame 10 as at 14, and carries a bucket or scoop 13 at one end, adapted to pick up and carry a load of material such as earth, gravel, crushed rock, or the like. It will be plain that swinging of the arm 12 about the pivot 14 serves to raise and lower bucket 13.

In order to control such swinging movement, a cable element 15 which cooperates with a winding drum mechanism 26 is provided. This mechanism may include a friction clutch or the like

for operatively connecting the drum with a source of power, so as to be positively driven, as well as brake means for restraining rotation of the drum. As shown, this element 15 is operatively connected to the bucket 13 for the purpose of controlling the bucket 13 which may be pivotally attached at 27 to the arm 12, for movement with respect to the arm. Since the bucket 13 and the arm 12 are each supported for movement in parallel planes, the cable element 15 may control in addition the arm 12.

As clearly shown in Figure 2, the bucket 13 and the arm structure 12 are relatively wide and in order to properly support them, the supporting force exerted by the cable element 15 should be applied at widely spaced points as 16 and 17. To do this conveniently, the cable element 15 may have a pair of reaches 18 and 19 which are respectively operatively connected to the bucket 13 at the points 16 and 17. By applying simultaneously acting equal forces on the cables 18 and 19, the bucket 13 is lifted or controlled without distortion and without developing twisting or weaving stresses in the arm 12, frame 10, or other parts of the machine.

However, due to various factors, such as the difficulty of initially adjusting separate cables to insure equal tension in both cables, unequal distribution of the load in the bucket 13, wear of the working parts, etc., it is desirable to provide some means for automatically ensuring that the tension in the cables 18 and 19 is equal at all times and under all load conditions. Accordingly, the cable reaches 18 and 19 are united by a lateral section 20, 21 to form a bridle for supporting the bucket and arm assembly, and sheave wheels 22 and 23 over which the cable 15 passes are provided to form the points of attachment 16 and 17. With this arrangement, if the tension in one reach of the cable, for example 18, exceeds that in the other reach 19, a slight movement of the cable toward the higher tensioned reach will occur about the sheaves 22 and 23, shifting the lateral portion 20, 21 of the cable slightly to the right (Fig. 2).

To accommodate movement of the bucket 13 about the pivot 27, with respect to arm 12, the sheaves 22 and 23 are attached to the bucket so as to be swingable about axes parallel to the axis of the pivot 27. Thus, the sheaves 22 and 23 are rotatably supported on pins 51 and 52, which in turn are carried in U-shaped members 53 and 54. The members 53 and 54 respectively are mounted on pins 55 and 56 secured to the back plate 32 of the bucket by ears 57. Members 53 and 54 are joined by parallel bars 58 and 59 to form a bridge structure or frame 60.

It is also desirable to prevent shock or impact loads being imparted to the cable 15 and other parts of the mechanism by the bucket 13. Such shocks may be very severe upon the sudden application of the brake means on the winding drum mechanism to check the descent of the loaded bucket, or they may result from one corner of the bucket striking hard material, such as a boulder, during digging operations. Accordingly, it is desirable to provide means for introducing resilience into the cable 15.

In the instant case, a shock absorbing means is provided wherein the resilience is provided by a compression spring so arranged that the lateral portions 20, 21 of the cable 15 have a toggle action with respect to the spring and only a small part of the tension in the cable acts on the spring. 75

Further, to avoid over stressing one reach 18 or 19 of the cable 15 under an impact load before the equalizing means has a chance to act, it is desirable to place the shock absorbing means symmetrically in the cable system. Accordingly, the shock absorbing means, indicated by 25, is mounted on the bridge 60 intermediate the sheaves 22 and 23.

As shown in Figure 3, the shock absorbing means 25 includes a hollow cylindrical member 30 open at one end and provided with a base 31 at its opposite end, the base 31 being secured as by welding to the bars 58 and 59 of the bridge 60. Slidable over the cylinder 30 is a tubular member 33, and confined between the base 31 and the head 34, is a compression spring 35, urging the member 33 outwardly of the cylinder. An adjustable stop 36 may be provided to maintain the parts in assembled relationship until the cable element 15 is installed.

Secured to the head 34 is a saddle member 39, having an arcuate groove 40 for accommodating the laterally extending portions 20, 21 of the cable 15.

Since the sheaves 22 and 23 and shock absorber 25 are all mounted on the bridge structure 60, they are maintained against relative movement, but can move as a unit with respect to the bucket 13. Thus, no misalignment or cramping of the parts can occur as the bucket 13 moves with respect to arm 12, and the laterally extending portions 20, 21 of the cable element are maintained in the same plane with respect to the sheaves and shock absorber for all positions of the bucket 13.

The operation of the mechanism may now be described. As previously explained, any inequality in the tension of the reaches 18 and 19 of the cable 15 is equalized by a slight shifting of the lateral portion 20, 21 of the cable toward the reach that is most heavily loaded, this movement causing slight rotation of the sheaves 22 and 23 as well as causing the portions 20, 21 to slip on the saddle 39. Otherwise, the cable 15 does not move with respect to the frame 60, that is, it has no translatory movement with respect thereto.

From an inspection of Figure 2, and considering the ends of the cable reaches 18 and 19 as fixed, it will be plain that the force of the spring 35 tends to increase the length of the cable in the lateral portions 20, 21 and reducing the effective lengths of the reaches 18, 19. Thus, any impact load acting either on the bucket 13 or on the cable 15 tending to increase this effective length is yieldingly opposed by the spring 35. Shocks to the mechanism are thereby avoided.

The lateral portions 20 and 21 of the cable by forming less than a straight angle with each other, have an action on the spring analogous to that of a toggle. That is, a substantial change in this angle, corresponding to a considerable change in the height of the spring 35, will result from only a slight change in the effective lengths of the cable reaches 18, 19. Consequently, a comparatively light spring at 35 will suffice to hold relatively large tension forces in the cable 15.

Under certain conditions of operation, it may be desirable to equalize the tension in the cable element and then secure the cable element in such equalized condition and utilize only the shock absorber.

For this purpose, means are provided to clamp the lateral portion 20, 21 of the cable to the saddle. Thus, a piece 45 spanning the groove 40

is secured to the saddle 39. A bolt 46 is threaded through the piece 45 and carries a plate 47 adapted to engage the cable. It will be apparent that appropriate rotation of the bolt 46 will serve to force the plate 47 against the cable and clamp it against movement relative to the saddle. This means also acts, even when not clamped, to prevent the cable jumping out of the saddle 39, should the cable become slack for any reason.

A modified form of shock absorber is shown in Figure 5. Therein, a sheave 50 is rotatably mounted on the end of the tubular member 33, and carries the lateral portions 20 and 21 of the cable, after the manner of the saddle 39. In this arrangement, the frictional drag of the cable across the saddle, which in some cases might be considerable, is eliminated and more perfect as well as more immediate equalization of the forces in the two cable reaches 18 and 19, can be achieved.

I claim:

1. In a material handling apparatus, a material engaging element and arm assembly mounted for movement to raise and lower said element, a pair of transversely spaced sheaves mounted on said assembly, force exerting mechanism for controlling said movement and including a cable element operatively connected to the assembly by means of said sheaves, and having a portion extending between the sheaves, and mechanism carried by said assembly between said sheaves including a compression spring acting on that portion of the cable between the sheaves for absorbing impact loads on the cable, the force of the spring opposing the force in the cable and acting transversely thereto.

2. In material handling apparatus, a material engaging element, an arm on which said element is mounted for movement with respect to said arm, said arm being mounted for movement to raise and lower said element, means for controlling said movement comprising a cable element, a bridge structure movably mounted on said material engaging element and extending transversely thereof, a pair of sheaves mounted on said structure at spaced points, said cable element passing about and between said sheaves, whereby the forces acting on the structure at said points are equalized, a member acting on the cable between said sheaves permitting resilient movement between the cable and said structure, said member being so positioned with respect to the cable that tension in the cable is opposed by said member in a direction transverse to the cable.

3. In load handling apparatus including a cable element, a frame member, spaced means at a fixed distance apart connecting said cable with said frame, a compression spring mounted on said frame between said spaced means, and engaging said cable element, said cable element being adapted to be connected at one end to force exerting mechanism and at the other end to means for maintaining the cable against substantial translatory movement with respect to the frame during transfer of force between the cable and the frame, said spring serving to vary the extent to which the cable is bowed out of alignment in accordance with the force acting on the cable, thereby absorbing impact loads on the cable.

4. In material handling apparatus, a material engaging element and arm assembly, mounted for movement to raise and lower said element, means for controlling said movement, including a cable

element operatively connected to said assembly, a compression spring for exerting a force transversely to tension in the cable, the force of said spring maintaining the cable bowed out of alignment for absorbing impact loads acting in the cable.

5. In material handling apparatus, a material engaging element and arm assembly, mounted for movement to raise and lower said element, means for controlling said movement including a cable element, a bridge structure movably mounted on said assembly and extending transversely thereof, means movably securing said cable to said structure at a pair of spaced points, said cable passing between said points whereby the forces acting on said structure at said points are equalized, and means carried by said structure intermediate said points, exerting a resilient force on the cable acting transversely thereof and opposing the force in the cable, for maintaining the cable bowed out of alignment between said points.

6. In material handling apparatus, a material engaging element and arm assembly, mounted for movement to raise and lower said element, means for controlling said movement, including a cable element, a bridge structure movably mounted on said material engaging element and extending transversely thereof means movably securing said cable to said structure at a pair of spaced points, said cable passing between said points whereby the forces acting on said structure at said points are equalized, and means carried by said structure intermediate said points, exerting a resilient force on the cable acting transversely thereof and opposing the force in the cable, for maintaining the cable bowed out of alignment between said points.

7. In material handling apparatus, a material engaging element and arm assembly, mounted for movement to raise and lower said element, means for controlling said movement, including a cable element operatively connected to said assembly at a pair of spaced points, said cable passing between said points whereby the forces acting on said assembly at said points are equalized, a pair of elements in telescopic relation interposed between said assembly and the cable intermediate said points, and means resiliently urging said members apart whereby a force is exerted on the cable transversely thereof and opposing the force in the cable for maintaining the cable bowed out of alignment between said points.

8. In material handling apparatus, a material engaging element and arm assembly mounted for movement to raise and lower said element, a pair of transversely spaced sheaves mounted on said element, force exerting mechanism for controlling said movement and including a cable element connected to the material engaging element by means of said sheaves, and having a portion extending between the sheaves, and mechanism carried by said material engaging element between said sheaves, acting on that portion of the cable between the sheaves for absorbing impact loads on the cable, said mechanism exerting a force opposing the force in the cable and acting transversely thereto.

9. In material handling apparatus, a material engaging element and arm assembly mounted for movement to raise and lower said element, means for controlling said movement comprising a cable operatively connected to said assembly at a pair of spaced points, said cable passing between said points whereby the forces acting on said assem-

bly at said points are equalized, and mechanism carried by said assembly between said points, including a compression spring acting on that portion of the cable between the points for absorbing impact loads on the cable, the force of the spring opposing the force in the cable and acting transversely thereto.

10. In material handling apparatus, a material engaging element and arm assembly mounted for movement to raise and lower said element, means for controlling said movement comprising a cable

5 operatively connected to said element at a pair of spaced points, said cable passing between said points whereby the forces acting on said element at said points are equalized, and mechanism carried by said element between said points acting on that portion of the cable between the points for absorbing impact loads on the cable, said mechanism exerting a force opposing the force in the cable and acting transversely thereto.

WILLIAM RUDDOCK.
